UNITED STATES PATENT OFFICE.

WILLIAM SEIDEL, OF CHICAGO, ILLINOIS.

WHEEL.

1,315,043.

Specification of Letters Patent.

Patented Sept. 2, 1919.

Application filed May 11, 1918. Serial No. 233,826.

To all whom it may concern:

Be it known that I, WILLIAM SEIDEL, a citizen of the United States, residing at Chicago, county of Cook, and State of Illinois, have invented certain new and useful Improvements in Wheels, of which the following is a specification.

This invention relates to an improved vehicle wheel, the principal objects being 10 simplicity, cheapness, lightness, strength, and resiliency. Numerous other objects are in contemplation as well, as will more fully hereinafter appear from the specification and claims, and from the accompanying 15 drawings, in which—

Figure 1 is a side view of a wheel embodying my invention, one casing section and one cushioning element being removed to exhibit certain of the interior parts;

20 Fig. 2 is an enlarged sectional view through one of the wheel spokes;

Fig. 3 is an enlarged cross section, taken on line 3—3 of Fig. 1;

25 Fig. 4 is a similar view, taken on line 4—4 of Fig. 1;

Fig. 5 is an enlarged detail in cross section, taken on line 5—5 of Fig. 1;

Fig. 6 is a cross section, taken on line 6—6 of Fig. 2;

30 Fig. 7 is a similar view, taken on line 7—7 of Fig. 2;

Fig. 8 is a side elevation of substantially one-half of a wheel of slightly modified construction;

35 Fig. 9 is an enlarged sectional view through one of the spokes of the wheel exhibited in Fig. 8; and

Fig. 10 is an enlarged detail in cross section, taken on line 10—10 of Fig. 8.

40 The suggested embodiment of my present wheel shown in Fig. 1 employs two complementary casing sections 11 arranged to provide between them a chambered space within which certain resilient elements are contained. Each casing section is shaped to provide a peripheral flange 12 adapted to receive reinforcing angle rings 13 upon which are mounted divided rim sections 14, such, for example, as are shown in Figs. 2 and 3. Flanges 15 are formed on the rim sections to grip a tire casing 16. The rim, tire flange, and tire construction may obviously be varied to suit requirements, an alternate arrangement being reserved for 55 consideration in connection with Figs. 9 and 10, presently to be described.

As will be seen from Fig. 1, the casing sections are each flanged to provide a peripheral channel 17 connecting with which are radial spoke channels 18 which open into an 60 annular channel in the region of the wheel hub. Entering for a slight distance into this annular channel is the wheel hub itself, designated as 19, which, in the form shown in Fig. 2, consists of two complementary 65 sections conveniently secured together as by bolts 20 (see Fig. 1). The casing sections are also held in unitary relation by some such device as tie bolts 21 located at convenient intervals. Extending radially from 70 the hub are spokes 22 whose inner ends may be appropriately configured, as by means of grooves 23, to enter into locking engagement with the hub which is formed with co-operating elements 24 for this purpose. The 75 outer end of each spoke may be in the form of an eye 25, through which extends a circular core piece 26 occupying a central position within the peripheral channel 17, each spoke eye 25 being preferably welded to the 80 core piece.

The parts thus far described include a hub which is loose with respect to the wheel casing, and a series of spokes fixed to the hub and to the core piece which lies within 85 the peripheral channel of the casing. The remaining wheel parts are formed from some material having resilient properties, such, for example, as rubber, or a rubber composition, and include a plurality of elements 27 equal in number to the number of spokes, each element being in the general form of the letter H with a straight connecting portion 28, the remaining portions 29 and 30 being each shaped in the form 90 of an arc struck from a common center. The straight portions 28 of these resilient elements 27 are arranged to lie within the spoke channels 18, the arc portions 29 within the peripheral channel 17, and the other 100 arc portion 30 within the annular channel adjacent the hub. As will appear from the several figures of the drawing, the resilient elements 27 are formed around the spokes 22 and the core piece 26, this being accomplished either by the process of molding, or by forming each element of two sections held in complementary relation when positioned operatively between the casing sections of the wheel. In order that these 105 resilient elements may not be unduly heavy and at the same time be free to operate with

greater freedom, annular channels 31 are provided exteriorly thereof (see Figs. 1 and 2), and pockets 32 interiorly thereof, the pockets and channels being preferably arranged in alternate order.

Referring now to the construction shown in Figs. 8, 9, and 10, it will be noted that the wheel is in all substantial respects the same as the device shown in Fig. 1. Accordingly I have designated the casing sections, the interior channels, resilient elements, etc., by the same numerals as those applied to the corresponding parts of the wheel already described. The principal point of departure is in the tire rim which dispenses with the reinforcing angle rings. As best shown in Fig. 9, the casing flanges 13 form the felly on which the tire is mounted, demountable rims 33 being secured to the sides of the casing section by means of the tie-bolts 21. Each of these demountable rims is formed with a tire retaining flange 34 and a casing engaging flange 35 around which fits a ring 36. It is apparent that the tire flanges may be removed by simply unscrewing the nuts from the bolts 21, whereupon the rings 36 may be taken off, permitting the tire rims 33 to be demounted.

The present wheel is characterized by certain interior channels formed adjacent its periphery, adjacent its hub, and in the spokes, and by the presence of resilient elements within these channels tending to keep the hub centered with respect to the wheel periphery. This construction is such that shocks and bumps are easily and effectively absorbed without the necessity of an air cushion in the tire or elsewhere.

I claim:

1. A vehicle wheel comprising, in combination, a hollow casing, a hub movable radially of the casing, means for centralizing the hub relative to the wheel consisting of a plurality of spokes fixedly secured to the hub and radially extending therefrom, a ring-shaped member loosely arranged within the wheel casing in proximity to its rim and connected with each of the spokes, and a plurality of resilient elements surrounding the ring-shaped member and spokes and extending into the hub for normally maintaining the hub in a position centrally of the wheel, substantially as described.

2. A vehicle wheel comprising, in combination, complementary sections arranged to provide between them a peripheral rim channel, spoke channels connecting therewith, and a circular channel opening toward the center of the wheel, a hub disposed between the wheel sections and slightly overlapped thereby, spokes secured to the hub and extended through the spoke channels, a core extending within the peripheral channel and connected with each spoke, and resilient elements interposed between the hub and the walls composing the various channels within the wheel, substantially as described.

3. A vehicle wheel comprising, in combination, a rim, a hub, and spokes extended between the rim and hub, the spokes being fixedly secured to the hub and loosely secured to the rim, there being intercommunicating channels formed in the rim, spokes, and hub, and resilient elements positioned within the communicating channels, and extending from the rim through the spokes into the hub and tending to centralize the hub with respect to the wheel, substantially as described.

WILLIAM SEIDEL.
